PAPER RUPTURE PISTOL

Anthony N. Smith, Girard, Pa., assignor to Louis Marx & Company, Inc., New York, N. Y., a corporation of New York

Application October 29, 1936, Serial No. 108,161

18 Claims. (Cl. 46—195)

This invention relates to toys, and more particularly to a toy weapon which produces a percussive report by pneumatically rupturing paper.

The object of my invention is to generally improve toy weapons, especially of the paper rupture type. More particular objects center about and are to improve the mechanism for retracting and releasing the piston, the mechanism for operating the paper clamping or paper sealing device, and the mechanism for holding and feeding the paper in the toy.

To the accomplishment of the foregoing general and other more particular objects which will hereinafter appear, my invention consists in the paper rupture toy elements and their relation one to the other as hereinafter are more particularly described in the specification and sought to be defined in the claims. The specification is accompanied by drawings in which:

Fig. 1 is a side elevation of a toy pistol embodying features of my invention, with one side of the pistol casing almost wholly cut away;

Fig. 2 is a horizontal section taken in the plane of the line 2—2 of Fig. 1;

Fig. 3 is a section taken in elevation in the plane of the line 3—3 of Fig. 2;

Fig. 4 is a similar view showing the relation of the parts near the end of the trigger movement;

Fig. 5 is a similar view showing the relation of the parts at the end of the trigger movement;

Fig. 6 is a transverse section taken in the plane of the line 6—6 of Fig. 1; and

Fig. 7 is a horizontal section taken in the plane of the line 7—7 of Fig. 1 and showing the paper feed mechanism.

Referring to the drawings, the paper rupture toy simulates a pistol adapted for rapid firing. The pistol comprises a cylinder 12 mounted near the muzzle of the gun, and a piston 14 reciprocable in said cylinder. The piston is secured at the forward end of a piston rod 16 around which is coiled a main compression spring 18. The forward end of spring 18 bears against piston 14, and the rear end of spring 18 bears against the forward wall 20 of a frame 22 mounted within pistol body 24. The piston is thus normally urged forward by spring 18 to the position shown in Figs. 1, 2, and 3.

A strip of paper P is fed past the muzzle of the gun from a paper roll R by appropriate paper feed means F. The paper is clamped against the muzzle of the gun by a clamping ring C, as is clearly shown by the change in the relation of the parts from Fig. 3 to Fig. 4. The piston is then released without, however, releasing the clamp C, and the resulting compression of air within the cylinder bursts the paper film at the muzzle of the gun, with a loud report. The relation of the parts at this time immediately after firing the gun, is shown in Fig. 5. The clamp C

is then released and a new section of paper is fed to the muzzle of the gun, as is indicated in Fig. 1. The various movements above outlined are obtained by a simple pull on trigger T which, during the first part of its movement, draws the piston rearwardly to tension the main spring 18, and also draws the clamp ring C rearwardly to seal the paper at the muzzle of the gun. At the end of the trigger movement the piston is abruptly released without, however, releasing the clamp C, thus firing the gun. During the forward or return movement of the trigger, the clamp C is released and the paper is fed forwardly from the paper roll.

Considering in greater detail the mechanism by which this desired operation is accomplished, the trigger T is oscillatably mounted at its upper end on a pin 26 extending transversely through the frame 22. As is best shown in Fig. 2, the side walls of the frame are indented at 28 to prevent sideward movement of the trigger and to countersink the riveted ends of pin 26. In the particular arrangement here illustrated, the pin 26 is located at the same elevation as the piston rod 16, and the latter is therefore slotted at 30 to afford free reciprocation of the rod with respect to pin 26.

Trigger T is made of a single piece of sheet metal which is reversely bent to have a U shape in section. The trigger is thus formed with side walls 32 and a forward wall 34. The latter is preferably rounded and may be given a sinuous or indented shape to more readily fit the fingers of the operator. The trigger does not require and is preferably devoid of rear and bottom walls. The side walls 32 are projected upwardly to receive the pivot pin 26, but the forward wall 34 is terminated well below the piston rod 16, thus enabling the piston rod to pass between the side walls 32.

Trigger 32 carries a cam element 36, and piston rod 16 is provided with a cooperating cam follower 38. As is best shown in Fig. 2, the cam follower 38 preferably passes through and projects on opposite sides of the piston rod 16. Cam element 36 is preferably formed of a single piece of sheet metal bent upwardly to form side walls 40 adapted to straddle the piston rod 16, and a bottom wall 42 which interconnects the side walls 40. The entire element is pivotally mounted on trigger T by means of a pin 44. The element 36 is normally urged in a clockwise direction by means of a wire spring 46 the upper end 48 of which bears against the top of the pistol body, and the lower end 50 of which passes through a hole in bottom wall 42, as is best shown in Fig. 3. The resulting oscillation of cam element 36 is limited by motion-limiting stop lugs 52 struck inwardly from the side walls 32 of the trigger.

It will be clear from inspection of Fig. 3 that

as trigger T is drawn rearwardly, the cam element 36 moves upwardly and rides in front of the cam follower 38. The shape of the rear edge of cam element 36 is such that as the trigger is moved, the cam element forces the cam follower and with it the piston rod rearwardly. Thus, in Fig. 4 the trigger is shown near the end of its rearward movement, and it will be noted that the upward movement of cam element 36 against cam follower 38 has forced the cam follower and piston rod rearwardly, the piston 14 then being near the rear end of cylinder 12. In the particular construction here illustrated, the rear end of the piston rod passes through the rear wall 54 of the frame 22 and through the rear end or breech of the pistol body. The frame 22 may, if desired, be provided with a bearing pin 56 carrying an anti-friction roller 58 beneath which the piston rod 16 rides. This is desirable in order to eliminate friction and in order to obtain smooth easy operation despite the upward component of force impressed on cam follower 38 by cam element 36 during its upward movement.

25 In order to release the piston rod at the end of the trigger stroke, the cam element 36 is preferably provided with an escape passage through which the cam follower 38 readily passes. Specifically the side walls 40 of the cam are displaced outwardly to form the channel-shaped passages 60 which are most clearly shown in Figs. 2 and 6. The width of the channels or passages 60 exceeds the diameter of the cam follower 38, and the outward displacement of the passages is such that the distance therebetween exceeds the axial length of the cam follower. Referring to Fig. 4, it will be seen that near the end of the trigger stroke the escape passage 60 approaches the cam follower 38; and referring to Fig. 5 it will be seen that at the end of the trigger movement the escape passage 60 is brought into direct alignment with cam follower 38, thus permitting the latter to shoot forwardly through the cam element 36.

On releasing the trigger, the spring 46 previously mentioned functions to restore the trigger to the forward position shown in Figs. 1 and 3. During this return movement of the trigger the cam element 36 oscillates counter-clockwise away from the motion-limiting stops 52, this movement being caused by engagement of the forward edge of the cam element with the cam follower 38. When, however, the trigger reaches its foremost position, the end of cam element 36 passes below cam follower 38, and the cam element is oscillated in a clockwise direction against motion-limiting stops 52 and assumes the initial position shown in Figs. 1 and 3. At this time the relation of the parts is such that on pulling the trigger rearwardly the cam element again comes in front of the cam follower and again functions to move the piston 14 rearwardly against the compression spring 18.

The mechanism for moving the clamping means C against the paper at the muzzle of the gun is next described. The clamping ring is preferably struck from heavy-gauge sheet metal and provided with a pair of long diametrically extending arms 62 which are bent rearwardly, as is best shown in Figs. 1 and 2, to form guide links for guiding and moving the ring. Guide links 62 pass outside of cylinder 12 but preferably inside of the pistol body, as will be clear from inspection of Figs. 1 and 2. The links are thus wholly concealed except for that portion which extends beyond the muzzle of the gun. Links 62 are stepped

inwardly somewhat at 64 and then extend rearwardly, as indicated at 66, in contact with the opposite sides of frame 22. The ends of the links are connected by a pin 68 which extends through and is movable in slots 70 (Figs. 1 and 2) cut through side walls of frame 22. Pin 68 also extends through a slot 72 (Figs. 2 and 3) cut through piston rod 16. Slot 72 is so located that piston rod 16 cannot move rearwardly without drawing the links 62 rearwardly with it, but the piston rod may move forwardly without the links, as is illustrated in Fig. 5. The links are normally urged forwardly by a spring 74 the U-shaped center portion 76 of which is anchored in the bottom of frame 22, and the forward ends 78 of which are anchored in appropriate lugs 80 bent inwardly from links 62. When the links are drawn rearwardly the spring is bent to the position shown in Figs. 4 and 5, but when the links are released the spring moves the links forwardly and assumes the position shown in Figs. 1 and 3.

To hold the links in retracted position in order to clamp and seal the paper membrane at the muzzle of the gun while the piston is impelled forwardly, I provide suitable stop means moved by and preferably mounted on the trigger T. The stop means is indicated at 82 and may be formed directly on the trigger, but in the present instance has been formed on the cam element 36. The side walls of the cam element are projected upwardly to form a pair of stops 82 so disposed as to straddle the piston rod 16 when the trigger is moved to rearward position. Thus, referring to Fig. 4, it will be seen that near the end of the trigger movement the stops 82 begin to move in front of the pin 68 which extends from one link to the other, and referring to Fig. 5 it will be seen that when the trigger is moved to rear-most position, thus releasing the piston rod for forward movement, the stops 82 are disposed directly in front of pin 68, thus holding the clamping ring C tightly against the muzzle of the gun. The rear edges of stops 82 may be given a slight curvature in order to obtain a camming pressure against pin 68, which insures air-tight sealing of the paper membrane.

Of course, on releasing the trigger the stops 82 move downwardly from in front of pin 68, and the links 62 and with them the clamping ring C are moved forwardly by spring 74.

The paper roll R turns about a stationary pin 84 which projects sidewardly from wall 86 (Fig. 7) of the gun housing. The pin is securely anchored to wall 86 at one end, the other end of the pin being left free and unsupported in order to facilitate the slipping of a roll of paper thereover. At the free end of pin 84 the gun housing is provided with a closure 88 pivotally mounted at 90 so that the closure may be moved rearwardly to the broken-line position shown in Fig. 4, at 88', thereby opening the paper chamber. The strip of paper is fed from the top of roll R along the upper side of a paper guide channel 92. This channel is curved smoothly upwardly and is secured to the clamping ring C by bent tongue connections 94. The side walls of the channel guide the paper accurately across the aperture 96 through the clamping ring, as is clearly shown in the drawings. Near the rear end of the paper guide channel 92 the side walls are enlarged and form supports 98 for a pin 100 on which is pivotally mounted a paper feed dog 102. The dog 102 is normally urged downwardly by a small leaf spring 104 the forward end of which is secured, as by welding, to dog 102, and the

5 rear end of which rests on a resilient member 106. As is best shown in Fig. 7, the dog 102 is a plate provided at its lower edge with a pair of tangs or points 108. The bottom surface of the paper 10
guide channel 92 is preferably depressed to form grooves 110 in which points 108 slide. This insures penetration of the paper by the points, and accurate feed of the paper. The points 108 are, of course, spaced apart an amount greater than 15 the diameter of the apertures in the muzzle of the gun and the sealing ring, and the minute perforations made by the points 108 do not affect the air-tightness of the paper membrane.

10 The member 106 is secured at its rear end to the bottom wall of the gun housing, the attachment preferably being at one edge, as is indicated by the eyelets 112 in Fig. 7. The advantage of attaching the member at one edge is that there is no interference with opening of the gun casting by separation of the halves thereof. The 20 forward end of member 106 rests on the paper being fed over the guide channel 92 and functions to frictionally restrain the paper against movement and to prevent escape of the paper from the guide channel. Moreover, the member 25 106 is made to act as a holding pawl for the paper, and to this end a pair of tangs or points 114 are formed on and struck downwardly from the member, the said tangs being aligned with the tangs 108 and being disposed over and cooperating with the grooves 110 previously referred to.

30 In operation, it will be understood that during rearward movement of the trigger and rearward movement of the clamping ring C, the feed dog 102 slides rearwardly over the paper in the guide channel 92, and the paper is prevented from moving rearwardly with the guide channel by the holding dogs 114. After the gun has been fired 40 and during release of the trigger, the clamping ring C moves forwardly, and at this time the holding dogs 114 merely slide over the paper, while the feed dog 102 draws a new section of paper from the paper roll R.

45 The casing or gun body 24 is preferably formed of two pieces of sheet metal each having a side wall and peripheral flanges adapted to be brought into edge to edge relation to complete the gun body. Simulated sights 120 may be used to hold the parts in registration, and these and other points on the gun body may be provided with appropriate tongue and slot connections one of which is indicated at 122 at the bottom of the gun handle. (The others have been omitted to 50 simplify the drawings.) At the muzzle of the gun the halves of the gun body are held together by a ring 124 which fits tightly over the gun body and which is recessed at the sides to receive the guide links 62. The forward end of cylinder 12 55 is flanged inwardly and the parts are provided with a rubber sealing ring or gasket 126 the nature of which will be clear from inspection of the drawings. This sealing ring provides a yieldable surface against which the paper may be compressed to form an air-tight seal.

60 The frame 22 is made up of two pieces of heavy-gauge sheet metal bent to provide side walls and end walls secured together by appropriate bent tongue and slot connections indicated 65 at 127 (Figs. 1, 2, and 3). Referring to Figs. 2 and 6, it will be noted that the top and bottom edges of the side walls are turned outwardly to form spacer flanges 128 which centralize the frame between the side walls of the gun body. 70 75 The flanges 128 are preferably provided with

tongues 130 which pass through mating slots in the gun body and are bent to securely lock the frame 22 within the gun body.

It is believed that the construction and operation as well as the many advantages of my improved paper rupture gun, will be apparent from the foregoing detailed description thereof. The gun is both cocked and fired by movement of the trigger alone, yet the trigger movement is made smooth and easy by the cam mechanism employed 10 for compressing the main spring. The manner in which the clamping ring is held in paper sealing position while the piston is released for forward movement, insures dependable operation of and long life for the mechanism. The paper is 15 tightly sealed and maintained in that condition during the firing stroke, and a loud report is obtained each time the gun is fired, regardless of how rapidly the trigger is repeatedly pulled.

It will be apparent that while I have shown and 20 described my invention in a preferred form, many changes and modifications may be made in the structure disclosed, without departing from the spirit of the invention, defined in the following claims.

25 I claim:

1. A toy gun comprising a cylinder, a piston movable therein, a piston rod extending from said piston, a spring for moving the piston in the cylinder, a cam follower on the piston rod, a 30 trigger, a cam on said trigger, said cam having an escape passage, the arrangement being such that when the trigger is drawn rearwardly the cam comes against the cam follower and tensions the spring until near the end of the trigger 35 movement when said cam follower shoots through the escape passage.

2. A toy gun comprising a cylinder, a piston movable therein, a piston rod extending rearwardly from said piston, a compression spring 40 surrounding said piston rod for moving the piston forwardly in the cylinder, a cam follower on the piston rod, a relatively large trigger, a cam element pivotally mounted on said trigger and having an escape passage, means to limit the oscillation of the cam element on the trigger, and resilient means normally urging the trigger forwardly, the arrangement being such that when the trigger is drawn rearwardly the cam element comes in front of the cam follower and forces the cam follower and piston rod rearwardly until near the end of the trigger movement when said cam follower shoots forwardly through the escape passage, said cam element oscillating on the trigger during the forward movement of the 45 trigger to change from a position in back of the cam follower to its original position in front of the cam follower.

3. A toy weapon of the paper rupture type comprising a cylinder, a piston movable therein, a piston rod extending therefrom, a cam follower on the piston rod, a spring for moving the piston, a paper clamping ring reciprocable at the end of the cylinder, means to move and hold the same against the cylinder during movement of the 50 piston, a trigger, a cam element thereon, said cam element having an escape passage, the arrangement being such that on movement of the trigger the cam element bears against the cam follower and tensions the spring until near the 55 end of the trigger stroke at which time the escape passage reaches the cam follower, thus abruptly releasing the piston.

4. A toy weapon of the paper rupture type comprising a cylinder, a piston movable therein, 60

- 5 a piston rod extending therefrom, a cam follower on the piston rod, a spring for moving the piston, a paper clamping ring reciprocable at the end of the cylinder, a guide link extending from said ring, a lost motion connection between the link and the piston rod whereby the piston rod cannot move rearwardly without the link but may move forwardly without the link, a trigger, a cam and stop element thereon, said cam having an 10 escape passage, the arrangement being such that on rearward movement of the trigger the cam element bears against the cam follower and tensions the spring until near the end of the trigger stroke at which time the stop element arrests 15 movement of the link and the escape passage reaches the cam follower, thus abruptly releasing the piston while holding the ring in clamped position.
- 20 5. A toy weapon of the paper rupture type comprising a cylinder, a piston movable therein, a piston rod extending rearwardly therefrom, a cam follower on the piston rod, a powerful compression spring normally urging the piston forwardly, a paper clamping ring reciprocable 25 against the forward end of the cylinder, a guide link extending rearwardly from said ring, a lost motion connection between the link and the piston rod whereby the piston rod cannot move rearwardly without the link but may move forwardly without the link, resilient means tending 30 normally to move the link forwardly, a relatively large trigger, a cam and stop element oscillatably mounted thereon and having an escape passage, and means to limit the movement of said element relative to the trigger, the arrangement being 35 such that on rearward movement of the trigger the cam element bears against the cam follower and draws the piston rod rearwardly until near the end of the trigger stroke at which time the stop element arrests forward movement of the link and the escape passage reaches the cam follower, thus abruptly releasing the piston rod and piston while holding the ring in clamped position.
- 40 45 6. A toy gun of the paper rupture type, said gun comprising a gun body, a cylinder, a piston movable therein, a paper clamping ring reciprocable against the end of the cylinder, a paper roll, and means to feed the paper past the ring, said means comprising a paper guide attached to and movable with said ring, a paper feed dog mounted on and bearing against said guide and movable therewith, and a paper holding dog mounted on said gun body and bearing against 50 said paper guide.
- 55 60 65 70 75 7. A toy gun of the paper rupture type, said gun comprising a gun body, a cylinder near the muzzle thereof, a piston movable therein, resilient means for moving the piston forwardly in the cylinder, a paper clamping ring reciprocable against the muzzle of the gun, a compartment in said gun body for a paper roll, a door for access to said compartment, and means to feed the paper past the muzzle of the gun, said means comprising a paper guide attached to and movable with said ring, a paper feed dog mounted on and bearing against said guide and movable therewith, and a paper holding dog mounted on said gun body and bearing against said paper guide.
8. A toy gun of the paper rupture type, said gun comprising a gun body, a cylinder having an aperture at one end, a piston movable in said cylinder, a paper clamping ring reciprocable 75 against the apertured end of the cylinder, a paper

roll, and means to feed the paper past the end of the cylinder, said means comprising a paper guide, a paper feed dog bearing against said guide and having a pair of spaced points, a paper holding dog bearing against said paper guide and having a pair of similarly spaced points, said guide having channels or grooves at the same spacing as and mating with said points, the spacing of the points and grooves being greater than the diameter of the cylinder aperture. 10

9. A toy weapon of the paper rupture type comprising a cylinder, a piston movable therein, a piston rod extending rearwardly therefrom, a cam follower on the piston rod, a spring for moving the piston, a paper clamping ring reciprocable at the end of the cylinder, means to move and hold the same against the cylinder during movement of the piston, a trigger, a cam element thereon, said cam element having an escape passage, the arrangement being such that on rearward movement of the trigger the cam element bears against the cam follower and tensions the spring until near the end of the trigger stroke at which time the escape passage reaches the cam follower, thus abruptly releasing the piston, a paper feed 15 guide attached to and movable with the ring, and a paper feed dog mounted on and bearing against the guide, and a stationary paper holding means also bearing against the guide. 20

10. A toy weapon of the paper rupture type, comprising a pistol-simulating body, a cylinder at the muzzle thereof, a piston movable therein, a piston rod extending rearwardly therefrom, a cam follower thereon, a spring urging the piston forwardly, a paper clamping ring reciprocable 35 against the muzzle of the pistol, guide links connected to said ring and extending rearwardly therefrom outside the cylinder but inside the pistol body, a pin extending between the rear ends of said links and passing through a longitudinal slot on said piston rod, whereby the piston rod cannot move rearwardly without the links but may move forwardly without the links, a wire spring tending normally to move the links forwardly, a trigger having a cam with an escape 40 passage, a stop element on said trigger, the arrangement being such that on rearward movement of the trigger the cam moves against the cam follower and draws the piston rod rearwardly until near the end of the trigger stroke 45 at which time the stop element arrests forward movement of the links, and the escape passage reaches the cam follower, thus abruptly releasing the piston. 50

11. A toy weapon of the paper rupture type, comprising a gun-simulating body, a cylinder therein, a piston movable therein, a piston rod extending rearwardly therefrom, a cam follower extending through and exposed on each side of said piston rod, a spring urging the piston forwardly, a relatively large trigger having its upper end oscillatably mounted within the gun body and having its lower end exposed and movable, a double-walled cam element oscillatably mounted on the trigger in such position as to straddle the piston rod, the lower parts of said cam walls being bent outwardly to form an escape passage larger than the cam follower, the arrangement being such that on rearward movement of the trigger the cam element rides upwardly against the cam follower and draws the piston rod rearwardly until near the end of the trigger stroke at which time the escape passage reaches the cam follower, thus abruptly releasing the piston. 60

12. A toy weapon of the paper rupture type, 65

comprising a pistol-simulating body, a cylinder at the muzzle thereof, a piston movable therein, a piston rod extending rearwardly therefrom, a cam follower extending through and exposed on 5 each side of said piston rod, a spring urging the piston forwardly, a paper clamping ring reciprocable against the muzzle of the pistol, guide links connected to said ring and extending rearwardly therefrom outside the cylinder but inside 10 the pistol body, a pin extending between the rear ends of said links and passing through a longitudinal slot on said piston rod, whereby the piston rod cannot move rearwardly without the links but may move forwardly without the links, 15 a wire spring tending normally to move the links forwardly, a trigger oscillatably mounted on the pistol body, a double-walled cam element on the trigger in such position as to straddle the piston rod, the lower parts of said cam walls being 20 bent outwardly to form an escape passage larger than the cam follower, a stop element on said trigger, the arrangement being such that on rearward movement of the trigger the cam element rides upwardly against the cam follower and 25 draws the piston rod rearwardly until near the end of the trigger stroke at which time the stop element comes in front of the aforesaid pin on the links and arrests forward movement of the links, and the escape passage reaches the 30 cam follower, thus abruptly releasing the piston.

13. A toy weapon of the paper rupture type, comprising a pistol-simulating body, a cylinder at the muzzle thereof, a piston movable therein, a piston rod extending rearwardly therefrom, a cam follower extending through and exposed on 35 each side of said piston rod, a powerful compression spring urging the piston forwardly, a paper clamping ring reciprocable against the muzzle of the pistol, guide links connected to said ring and extending rearwardly therefrom outside the cylinder but inside the pistol body, a pin extending between the rear ends of said links and passing through a longitudinal slot on said piston rod, whereby the piston rod cannot move rearwardly without the links but may move forwardly without the links, a wire spring tending 40 normally to move the links forwardly, a relatively large trigger having its upper end oscillatably mounted within the pistol body and having its lower end movable into the handle of the pistol body, a double-walled cam element oscillatably mounted on the trigger in such position as to straddle the piston rod, the lower parts of said cam walls being bent outwardly to form 45 an escape passage larger than the cam follower, a stop element on said trigger, the arrangement being such that on rearward movement of the trigger the cam element rides upwardly against the cam follower and draws the piston rod rearwardly until near the end of the trigger stroke at which time the stop element comes in front of the aforesaid pin on the links and arrests forward movement of the links, and the escape passage reaches the cam follower, thus abruptly releasing the piston.

14. A toy weapon comprising a trigger, a cam element oscillatably mounted thereon, a cylinder, a piston movable therein, a main spring for actuating said piston, said cam element functioning to tension said spring, stop means on said trigger for limiting the oscillation of said cam element relative to said trigger, and a single spring for normally oscillating the cam element against the

stop means on the trigger and for oscillating the trigger to its forward position.

15. A toy gun of the paper rupture type, said gun comprising means to compress air, a paper sealing ring reciprocable in front of the muzzle 5 of the gun, a pair of guide links secured to said paper sealing ring and extending rearwardly therefrom at opposite sides of the barrel of the gun, means to reciprocate said guide links in order to clamp said ring against the muzzle of 10 the gun, and a paper guide channel and paper feed means mounted on and reciprocable with said paper clamping ring, said means being disposed beneath the muzzle of the gun and being supported and moved by said paper clamping 15 ring.

16. A toy gun of the paper rupturing type, said gun comprising an air-compressing cylinder, a gun body made of separable halves the muzzle portions of which surround and hold the cylinder, a muzzle ring comprising a band encircling and holding the halves of the gun body together at the muzzle, and an inturned flange in front of the muzzle, said cylinder also having an inturned flange at the muzzle of the gun, a rubber sealing 20 ring fitting over both said flanges, said rubber sealing ring being channeled on its exterior to receive said flanges, a paper clamping ring outside the muzzle of the gun, and means to move the same against the aforesaid rubber sealing 25 ring, said rings being apertured for the discharge of compressed air against a paper membrane held at the muzzle of the gun between the rings.

17. A toy weapon of the paper rupture type comprising a cylinder, a piston movable therein, a piston rod extending rearwardly therefrom, a compression spring normally urging the piston forwardly, a paper clamping ring reciprocable against the forward end of the cylinder, a guide link extending rearwardly from said ring, a lost motion connection between the link and the piston rod whereby the piston rod cannot move rearwardly without the link but may move forwardly without the link, resilient means tending normally to move the link forwardly, a trigger, a stop element moved by said trigger, and means such that on rearward movement the trigger draws the piston rod rearwardly until near the end of the trigger stroke at which time the stop element arrests forward movement of the link and the piston rod is released while the ring is held in clamped position.

18. A toy weapon of the paper rupture type comprising a pistol-simulating body, a cylinder at the muzzle thereof, a piston movable therein, a piston rod extending rearwardly therefrom, a spring urging the piston forwardly, a paper clamping ring reciprocable against the muzzle of the pistol, guide links connected to said ring and extending rearwardly therefrom outside the cylinder but inside the pistol body, a pin extending between the rear ends of said links and passing through a longitudinal slot on said piston rod, whereby the piston rod cannot move rearwardly without the links but may move forwardly without the links, a spring tending normally to move the links forwardly, a trigger, a stop element moved by said trigger, the arrangement being such that rearward movement of the trigger draws the piston rod rearwardly until near the end of the trigger stroke at which time the stop element arrests forward movement of the links while the piston is released.

ANTHONY N. SMITH.
